ROLL SPRING TAPE TOY

Joseph Anello, Cahokia, Ill., assignor to Judy Deb Manufacturing Co., Inc., St. Louis, Mo., a corporation of Missouri

Filed July 15, 1965, Ser. No. 86,171

Term of patent 3½ years

(Cl. D34—2)

FIG. 1 is a front view of a roll spring tape toy embodying my new design, shown unrolled.

FIG. 2 is a rear view thereof.

FIG. 3 is a side edge thereof shown partly rolled.

FIG. 4 is a view similar to FIG. 3, shown completely rolled.

I claim:

The ornamental design for a roll spring tape toy, substantially as shown.
